2,481,908

CONTROL FOR FREE-PISTON UNITS

Kenneth C. Cooper, Portland, Conn., assignor to
 United Aircraft Corporation, East Hartford,
 Conn., a corporation of Delaware

Application January 30, 1945, Serial No. 575,344

10 Claims. (Cl. 230—56)

1

This invention relates to a control for a free-piston unit.

In adapting the free-piston unit to compressing media of different densities as, for example, when the unit is used in aircraft the effective volume of the compressor has been adjusted to compensate for the density changes by providing a number of rows of spill ports in the compressor cylinder with an arrangement for successively opening or closing the rows of ports as a result of changes in the density of the medium. A feature of this invention is the control of the spill ports as a function of the exhaust pressure from the engine cylinder or as a function of the scavenge pressure which is the discharge pressure of the compressor.

In the copending Kalitinsky application, Serial No. 550,886 (Patent 2,441,273), the bands which control the spill ports are moved in response to a master control which indicates changes in the end position of the piston stroke. A feature of this invention is the control of the ports from the master control and also from the exhaust pressure.

In double acting compressors the compressor cylinder may have separate rows of spill ports, one series of rows of ports controlling the effective volume of the compressor on its outward stroke and another series of rows of ports controlling the effective volume for the inward stroke. A feature of this invention is the control of the inner rows of ports (for the inner stroke) independently of the outer rows of ports and as a function of the scavenge or exhaust pressure of the unit.

In the copending Cooper application, Serial No. 550,876 (Patent 2,426,297), the location of the inner end of the piston stroke is controlled by adjusting the air spring pressure. Such a control necessitates a source of gas under a pressure different from the pressures incidental to the operation of the unit by which to charge the air spring. A feature of this invention is a control of the location of the inner end of the piston stroke by adjusting the inner rows of spill ports instead of by adjusting the pressure in the air spring.

Other objects and advantages will be apparent from the specification and claims, and from the accompanying drawings which illustrate an embodiment of the invention.

Fig. 1 is a sectional view through the free-piston unit.

Fig. 2 is a sectional view through the synchronizing linkage.

2

Fig. 3 is a sectional view showing the control for one of the rows of spill ports.

Fig. 4 is a sectional view of the master control and the valve by which the spill ports are controlled.

The unit shown includes an engine cylinder 10 having reciprocating pistons 12 and 14 to which compressor pistons 16 and 18 in cylinders 20 and 22 are integrally connected. Sleeves 24 and 26 attached to the compressor pistons complete the reciprocating piston assemblies. The sleeves in combination with stationary pistons 28 and 30 form air spring cylinders.

The piston assemblies are moved apart by the 15 burning of fuel injected into engine cylinder 10 through one or more nozzles 32. Air compressed in the air spring cylinders on the power stroke returns the piston assemblies. The assemblies are always maintained at equal distances from 20 the center of the engine cylinder by a linkage which may include racks 34 and 36, Fig. 2, extending from the piston assemblies and meshing with a pinion 38 on a shaft 40.

Intake manifold 42 which extends around the 25 compressor and engine cylinders, conducts air to intake valves 44 in the heads of the compressor cylinders through which air alternately enters opposite ends of the cylinders. The compressed air leaves the cylinders through discharge valves 30 46, also at opposite ends of the compressor cylinders and passes into a central scavenge chamber 48 and end chambers 50 and 52. These chambers may be interconnected by a scavenge manifold, not shown.

Compressed gas from the scavenge chambers 35 enters engine ports 54 and 56 which are uncovered by pistons 12 and 14 at the end of the power stroke, thereby permitting air to be blown through the engine cylinder. Gas in the engine cylinders 40 is discharged through exhaust ports 58 into exhaust manifold 60.

Each compressor cylinder has a number of 45 axially spaced vents 62, each in the form of a row of spill ports in the cylinders to permit air to discharge from the cylinder without compression. Each vent, or row of ports, may be individually controlled by a band 64, Fig. 3, extending around the cylinder between projecting ribs 66 extending from the cylinder, said band having 50 spaced openings 68 for alignment with the spill ports. The band is held in place by a fixed band 69 having openings 70 aligned with the spill ports. The ends of this band may be connected by a block 71 which engages over lugs 72 on the 55 ends of the band. The block has gear teeth 76

engaging with a gear segment 78 on a shaft 80. The particular port closure shown is claimed in the copending application of Kalitinsky, Serial No. 550,884 (Patent 2,441,272), filed August 23, 1944.

The intake manifold includes a housing 82 which may extend around the compressor cylinders, and end caps 82 and 84 on the housing forming passages to the intake valves at the outer ends of the compressors. The vents 82 open into the intake manifold.

In operation, assuming all the rows of ports are open and only a small quantity of air is compressed, if the stroke lengthens, as when the density decreases, with the compressor operating at altitude, or in changing the load, one or more of the rows of ports may be closed, beginning with the end rows, thus increasing the effective volume of the compressor. Each row, as will be apparent, may be partially open or closed as the control operates. The several rows of ports permit adaptation of the compressor to substantially any altitude or to any density of air being pumped, or to any load.

The rows of ports may be automatically opened and closed from the master control which produces a pressure change in a control fluid in response to changes in an operating characteristic of the unit, such as a change in the length of piston stroke. Referring to Fig. 4, the master control is actuated by a cam 86 turning with the pinion 38 as shown in Fig. 2. Since the pinion 38 is oscillated directly from the pistons the movement of cam 86 is proportional to the piston stroke.

Fluid under pressure from a constant pressure source enters a passage 88 in a casing 90 through a conduit 92. This passage intersects a bore 94 adjacent its outer end and a throttling screw 96 controls the rate of flow into bore 94. A branch passage 98 from passage 88 connects with a port 100 in bore 94. A plunger 102 in bore 94 has a groove 104 which connects a port 106 alternately with port 100 or with a port 108. Port 106 is connected by a passage 110 to the inner end of bore 94. Port 108 is connected by a channel 112 in casing 90 and in an adjoining casing 114 to the inner (left-hand) end of a bore 116 in casing 114. A piston 118 in bore 116 is moved to the right by a calibrated spring 120. A plunger 122 extends through the piston and carries on its projecting end a push rod 124. This rod carries a roller 126 held against cam 86 by a spring 128. Plunger 122 has a central passage 130 connecting with spaced grooves 132 and 134 in the plunger. Groove 132 aligns with openings 136 in a sleeve 138 carried by piston 118 and groove 134 is adapted to be uncovered by the end of sleeve 138 as the plunger is moved to the right by the cam as the pistons approach the outer ends of their strokes.

Fluid under pressure from the right-hand end of bore 94 enters the right-hand end of bore 116 through a connecting channel 140, moving piston 118 to the left against the spring 128. As plunger 122 is moved to the right by cam 86 the groove 134 is uncovered by sleeve 138 to permit discharge of fluid from the right-hand end of bore 116. The pressure in the right-hand end of bore 116 varies in accordance with the compression of the spring and as the piston stroke becomes shorter the piston 118 moves inward, increasing the spring tension and increasing the pressure at the end of bore 94.

Since the change in pressure on the right-hand end of plunger 102 is proportional to the change

in the location of the end position of the piston stroke, the pressure on the inner (left-hand) end of plunger 102 which balances the pressure on the outer end must vary in the same manner. In this way, the pressure in the discharge conduit 142 is proportional to the spacing of the actual end of the piston stroke from the extreme outer position of the piston, and changes in pressure in this conduit will be proportional to changes in the outer end position of the piston stroke. This pressure and change in pressure are used to move the control bands for the rows of spill ports.

The outer end of the plunger 122 may reciprocate in a chamber 144 having an outlet conduit 146 connected to a sump, not shown. The inner end of bore 116 may be connected by a conduit 148 to the conduit 146. A bellows 150 connected by a conduit 152 to passage 140 may be used for minimizing surges in the controls.

The spill port control includes a casing 152 having a bore 154 in which a plunger 156 is mounted. A port 158 is connected by a conduit 160 to a cylinder 162 forming a part of a hydraulic motor which includes a piston 164. The other end of the cylinder is connected by a conduit 166 to a port 168 in the casing 152. The casing also has an inlet port 170 which is alternately connected to the ports 158 and 168 by the plunger 156. Plunger 156 is moved toward the right by a spring 172, tension of which may be adjusted by a nut 174. A piston 176 in a bore 178 in a cap 180 on the casing engages a projecting pin 182 on the plunger. Fluid under pressure from the inner master control enters the end of bore 178 from conduit 142 to move plunger 156 against the spring. Piston 176 may have a small vent 184 and the inner end of bore 178 may be vented by a passage 186.

The piston rod 188 on piston 164 has a rack 190 engaging with a pinion 192 mounted on the shaft 80 by which the spill port band or bands are actuated. If the inner end positions of the piston stroke moves away from inner dead center the fluid pressure from the master control increases, moving plunger 156 to the left, thereby moving piston 164 to the right and moving the rod 190 in a direction to open the endmost row of ports, Fig. 1, that control the effective volume of the compressor on its inward stroke. If the piston stroke continues to move away from inner dead center the second and third rows of ports marked B and C in Fig. 1 are successively opened. If the end of the piston stroke moves toward inner dead center the reverse occurs and the rows of ports A, B and C are successively closed in the reverse order.

The rows of ports B and C may be controlled by bands, not shown, actuated by the same mechanism above described, by means of gear segments 194 and 196 mounted on the same shaft 80 that carries segment 78. This arrangement of the gear segments angularly spaced, as shown in Fig. 3, provides for the successive actuation of the bands.

In addition to controlling the spill ports as a function of the piston stroke they may also be controlled as a function of the engine exhaust pressure. To accomplish this, the exhaust duct 60 is connected by a conduit 194 to the end of casing 152 opposite to the piston 176. In this way, when the exhaust pressure is low the pressure from the inner master control acts mainly against spring 172. As the exhaust pressure increases, however, this pressure assists spring 172 and a greater pressure from the inner master control is necessary to move plunger 156.

The outer rows of spill ports may be controlled

by a mechanism, not shown, which may be actuated by an outer master control, as shown, for example in the above mentioned Kalitinsky application, Serial No. 550,886 (Patent 2,441,273). By controlling the outer rows of ports (which control the effective volume of the outward stroke of the compressor) independently of the inner rows, it will be apparent that the work of compression may be divided between the inner and outer ends of the compressor, thereby to obtain the desired stroke length and position of stroke at all loads.

By control of the ports as a function of the exhaust pressure, it is possible to maintain substantially a constant maximum pressure in the engine cylinder. This results from a change in the spill ports in response to changes in the exhaust pressure which has a predetermined relation to the scavenge pressure.

It is to be understood that the invention is not limited to the specific embodiment herein illustrated and described, but may be used in other ways without departure from its spirit as defined by the following claims.

I claim:

1. In a free-piston unit, a compressor cylinder, an engine cylinder having scavenge ports through which air under pressure from the compressor cylinder enters the engine cylinder, an exhaust port through which gas under pressure from the engine cylinder is discharged, a piston assembly in said cylinders, said compressor cylinder having a number of axially spaced circumferentially extending rows of spill ports, and closure members for said rows of ports, in combination with means for actuating said closure members successively and a device responsive to changes in the pressure of the exhaust gas from the engine cylinder for operating said actuating means.

2. In a free-piston unit, a compressor cylinder, an engine cylinder having scavenge ports through which air under pressure from the compressor cylinder enters the engine cylinder, an exhaust port through which gas under pressure from the engine cylinder is discharged, a piston assembly in said cylinders, said compressor cylinder having a number of axially spaced circumferentially extending rows of spill ports, and closure members for said rows of ports, in combination with means for successively actuating the closure members for closing the axially spaced ports in succession, and a device responsive to changes in the end position of the piston strokes for operating said actuating means.

3. In a free-piston unit, a compressor cylinder, an engine cylinder having scavenge ports through which air under pressure from the compressor cylinder enters the engine cylinder, an exhaust port through which gas under pressure from the engine cylinder is discharged, a piston assembly in said cylinders, said compressor cylinder having a number of axially spaced circumferentially extending rows of spill ports, and closure members for said rows of ports, in combination with means for actuating said closure members in response to changes in said exhaust gas pressure from the engine cylinder, means responsive to movement of the piston assembly for indicating the location of the end of the piston stroke, and means responsive to said indicating means for moving said closure members.

4. In a free-piston unit, an engine cylinder having scavenge and exhaust ports, a compressor cylinder, a piston assembly in said cylinders, said compressor cylinder having a number of axially

spaced circumferentially extending rows of spill ports, and closure members for each row of ports, in combination with means for actuating said closure members, a device responsive to changes in the pressure of exhaust gas from the engine cylinder, means responsive to movement of the piston assembly for indicating the location of the ends of the piston strokes, said device being responsive to said indicating means, and means operated by said device for controlling said closure members.

5. In a free-piston unit, an engine cylinder having scavenge and exhaust ports, a compressor cylinder, a piston assembly in said cylinders, said compressor cylinder having a number of axially spaced circumferentially extending rows of spill ports, and closure members for each row of ports, in combination with means for indicating the inner end positions of the strokes of the piston assembly, and means actuated by said indicating means and responsive to changes in the inner end positions of the piston strokes for moving said closure members.

6. In a free-piston unit, a compressor cylinder, an engine cylinder having scavenge ports through which air under pressure from the compressor cylinder enters the engine cylinder, and exhaust ports through which gas under pressure from the engine cylinders is discharged, a piston assembly movable in said cylinders, and an exhaust duct for the gas, said compressor cylinder having a number of axially spaced rows of spill ports, and closure members for closing the rows of ports, in combination with hydraulically actuated means for moving said closure members in predetermined sequence, a pressure responsive valve for controlling the supply of fluid to said hydraulic means, and a connection from said valve to the exhaust duct for movement of the valve in response to changes in exhaust pressure.

7. In a free-piston unit, a compressor cylinder, an engine cylinder having scavenge ports through which air under pressure from the compressor cylinder enters the engine cylinder, and exhaust ports through which gas under pressure from the engine cylinders is discharged, a piston assembly movable in said cylinders, and an exhaust duct for the gas, said compressor cylinder having a number of axially spaced rows of spill ports, and closure members for closing the rows of ports, in combination with hydraulically actuated means for moving said closure members in predetermined sequence, a pressure responsive valve for controlling the supply of fluid to said hydraulic means, a connection from said valve to the exhaust duct for movement of the valve in response to changes in exhaust pressure, means for indicating changes in the end position of the strokes of the piston assembly, and means responsive to said indicating means for moving said valve.

8. In a free-piston unit, a compressor cylinder, an engine cylinder having scavenge ports through which air under pressure from the compressor cylinder enters the engine cylinder, and exhaust ports through which gas under pressure from the engine cylinders is discharged, a piston assembly movable in said cylinders and an exhaust duct for the gas, said compressor cylinder having a number of axially spaced rows of spill ports, and closure members for closing the rows of ports, in combination with hydraulically actuated means for moving said closure members in predetermined sequence, a pressure responsive valve for controlling the supply of fluid to said hydraulic means, and a connection from said

valve to the exhaust duct for movement of the valve in response to changes in exhaust pressure, means for indicating changes in the inner end position of successive strokes of the piston assembly, and means responsive to said indicating means for causing movement of the valve.

9. In a free-piston unit, an engine cylinder having scavenge and exhaust ports, a compressor cylinder, a piston assembly in said cylinders, said compressor cylinder having a number of axially spaced spill ports, and closure members for each port, in combination with hydraulically actuated means for moving said closure means in sequence, a pressure responsive valve for controlling the supply of fluid to said hydraulic means, means responsive to the piston assembly movement for producing changes in pressure in a hydraulic circuit in response to changes in the end position of the strokes of the piston assembly, and a connection from said valve to said circuit to cause said valve to move in response to said changes in pressure.

10. In a free-piston unit, an engine cylinder having scavenge and exhaust ports, an exhaust duct connected to said ports, a compressor cylinder, a piston assembly in said cylinders, said compressor cylinder having a number of axially spaced spill ports, and closure members for each port, in combination with hydraulically actuated means for moving said closure means in sequence,

5 a pressure responsive valve for controlling the supply of fluid to said hydraulic means, means responsive to the piston assembly movement for producing changes in pressure in a hydraulic circuit in response to changes in the end position of the strokes of the piston assembly, a connection from said valve to said circuit to cause said valve to move in response to said changes in pressure, and a connection from said valve to said exhaust duct connected to said valve such that the exhaust pressure acts on the valve in opposition to the pressure from said change producing means.
